(57) **CLAIM**

The ornamental design for a projection light, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a projection light showing my new design;

FIG. 2 is a rear elevational view thereof;

FIG. 3 is a left side view thereof;

FIG. 4 is a right side view thereof;

FIG. 5 is a perspective view thereof;

FIG. 6 is a second perspective view thereof;

FIG. 7 is a third perspective view thereof; and,

FIG. 8 is a fourth perspective view thereof.

The part of the photograph shown in a coarser dot pattern within the broken-line perimeter, as well as the broken-line perimeter itself, illustrates a portion of the projection light that forms no part of the claimed design.
